LOOSE-LEAF BINDER

Fred W. Metzger, Los Angeles, Calif., assignor of
one-half to Henry Beck, Los Angeles, Calif.

Application September 12, 1932
Serial No. 632,712

6 Claims. (Cl. 129—36)

This invention relates to a loose-leaf binder and particularly to a loose-leaf binder which does not require punching or perforation of the loose leaves for insertion in the binder.

5 The principal object of the present invention is to provide a loose-leaf binder adapted to receive a plurality of unpunched leaves and secure the same against removal, and which is easily opened to allow of removal of one or more of said leaves.

10 The present invention is particularly adaptable for use as a "stock-binder" or any other form of "post" binder wherein a relatively large number of leaves are kept in a single binder and wherein it is necessary to remove, replace or add leaves at

15 rather frequent intervals. In this case, where the conventional form of "post" binder is used, it is necessary to remove the leaves above the point where a new leaf is to be inserted, punch the new leaf, place it over the posts, and then replace

20 the removed leaves over the posts, which latter operation usually requires considerable time and patience for the reason that the punch holes in the leaves must be kept in relative alignment in order to fit over the posts.

25 According to the present invention, the leaves are not punched, and when it is desired to remove a plurality of leaves from the binder, the binder may be loosened and the desired number of leaves removed bodily, a new leaf inserted, and 30 the removed leaves replaced bodily.

Further, leaves may be removed from, replaced in or new leaves added to the loose-leaf binder of the present invention by loosening said binder, placing it on its rearward end with the sheets held

35 vertically, in which position any one or a number of leaves may be withdrawn or inserted, without disturbing the neighboring leaves.

A further object of the present invention is to provide a loose leaf binder which may be constructed at a much lower cost than other types 40 of binders of comparable utility.

45 A further object of the present invention is to provide a loose-leaf binder of the character above described, provided with a "solid-back" construction, whereby full protection is afforded to the bound ends of the leaves in said binder.

In its essentials, the device of the present invention may comprise a pair of elongated clamp members between which a plurality of sheets of paper may be secured, said clamp members being preferably provided with a plurality of projections or points on their opposingly disposed surfaces adapted to press into the sheets or leaves and hold the same against lateral displacement, and

means securing said clamp members in clamping relation.

The device may further comprise one or a plurality of alignment members adapted to be inserted in position between said clamp members at intervals between groups of the leaves, said alignment members being preferably provided with projections or points in the same manner as are the clamp members, whereby complete placement and securing of the leaves is obtained when the aforesaid clamp members are brought in clamping relation by means of said securing means.

The upper or lower clamp member and the aforesaid alignment members are also preferably provided with positioning means such as vertically extending shoulders disposed along the rearward edge thereof, whereby the individual leaves or groups of leaves may be positioned within the binder in relative alignment with one another and with the binder.

The device may further comprise a construction in which the upper and lower clamp members are provided with cooperating shoulder means at their respective rearward edges, adapted to overlap and form a substantially continuous back for the binder, and the alignment members above-mentioned may also be provided with shoulder means cooperating with the aforementioned shoulder means on the upper and lower clamp members, whereby, when one or a plurality of said alignment members are in use in the binder, a substantially continuous "solid-back" is provided for said binder.

The accompanying drawing illustrates embodiments of my invention, and referring thereto:

Fig. 1 is an end elevation of a simple form of binder of the present invention, taken on line 1—1 in Fig. 3, with the alignment strips shown in dot-and-dash position, and the paper leaves omitted;

Fig. 2 is a plan view thereof, with the leaves broken away;

Fig. 3 is a side elevation thereof, showing but a few leaves in place, and the upper portion of 100 the binder shown in clamping position in dot-and-dash lines;

Fig. 4 is a perspective view of one form of alignment strip for use in the present invention;

Fig. 4a is a transverse sectional detail thereof 105 taken on line 4a—4a in Fig. 4;

Fig. 5 is a transverse sectional view of a modified form of the invention taken at a position corresponding to that shown at x—x in Fig. 1, 110

showing a plurality of leaves and one alignment strip in position;

Fig. 6 is a sectional view corresponding to Fig. 5, but taken at a position corresponding to that shown at $x'-x'$ in Fig. 1, showing the binder under compression;

Fig. 7 is a similar view of a further modified form of the invention, taken on line 7-7 in Fig. 8;

Fig. 8 is a rearward end elevation of the form of invention shown in Fig. 7, taken on line 8-8 therein;

Fig. 9 is a perspective detail of the form of alignment strip used in the form of device shown in Figs. 7 and 8;

Fig. 10 is a detail, in perspective, of a form of sectional screw-post which may be used with the present invention.

Referring to Figs. 1 to 5 of the drawing, the device of the present invention may comprise upper and lower clamp-members 1 and 2, said lower clamp-member 2 being provided with screw-posts 3 at opposite ends thereof, and said clamp-member 1 being provided with bores 3a corresponding to the position of said posts whereby said clamp-member may be placed on said posts in the position shown, in which position said clamp members and said posts serve to define a substantially unobstructed leaf-receiving space into which the edge portion of one or a plurality of unpunched leaves may be inserted. The device is provided with clamp-nuts 4 on the upper ends of said screw-posts, said screw-posts and said clamp-nuts comprising compression means for forcing the clamp-member 1 downwardly toward the clamp-member 2. The form of nut shown in the drawing is of the type adapted to grasp the threads on the screw-post only when actually forced into engagement with the clamp-member 1, and adapted to release said threads when backed away a short distance from said clamp-member. This is a conventional form of "clutch" nut and is particularly adaptable to the present invention, but it will be understood that any form of wing-nut, or the like may be used for the purpose.

The clamp-member 1 is preferably provided with a reinforcing web 1a extending along the upper edge thereof, whereby the rigidity of said member is made proportional to the stress applied thereto in the binding operation. The screw-posts 3 are preferably spaced sufficiently apart to allow for insertion of the paper leaves therebetween, as shown in Fig. 2.

The lower clamp-member 2 is preferably provided with a shoulder 2a extending along the rearward end thereof, the forward face of said shoulder being preferably disposed slightly rearwardly of the rearward edge of the upper clamp member 1, and adapted to receive the ends of the leaves, as shown particularly in Figs. 3 and 5, and align the same. This shoulder 2a is preferably provided with a plurality of notches 2b adapted to receive the depending lugs 6c of the alignment strip 6 disposed immediately above the lower clamp-member 2, as shown in dot-and-dash lines in Fig. 1. The alignment strips 6, shown in detail in Figs. 4 and 4a, are preferably formed from a single piece of relatively thin metal, such as steel, aluminum or the like, provided with an upwardly bent shoulder portion 6a having a plurality of notches 6b corresponding in number and position to the notches 2b in the shoulder 2a, the metal from the notches

6b being bent downwardly to form a plurality of projections or lugs 6c, above mentioned.

While the form shown in the drawing is provided with an upwardly extending shoulder on the lower clamp-member and on the alignment strip, it will be understood that downwardly extending shoulders may be provided on the upper clamp-member and the alignment strips, respectively, if so desired.

The upper wall of the clamp-member 2 and the lower wall of the clamp-member 1 are preferably provided with a plurality of pointed leaf-engaging projections 2c and 1b respectively, as shown in Figs. 1 and 5, which are adapted to engage the paper leaves adjacent said clamp-members and hold the same against lateral displacement or forcible removal when the binder is in binding position.

The method of use of the above described form of binder may be substantially as follows: With the upper clamp-member removed from the posts 3, or in a raised position such as shown in full lines in Fig. 3, one or a plurality of leaves A may be placed in position on the lower clamp-member 2, between the posts 3, and with their ends abutting the shoulder 2a. The upper clamp-member 1 is then lowered into the position shown in dot-and-dash lines at 1' and the screw-nuts 4 turned to force said clamp-member downwardly against the leaves A. When the clamp-members are thus brought in this position the body portions of said members will bear against said leaves, and the pointed projections 1b and 2c will be forced into tight engagement with the leaves immediately adjacent said clamp-members. I prefer to stagger the position of said pointed projections, so that, for example, a projection 2c will fall between two projections 1b, as shown in Fig. 1, this arrangement providing very secure holding of the leaves.

It is particularly pointed out that the projections 1b and 2c are primarily adapted to effect a holding action on the leaves by providing a plurality of points of increased compression along the clamp-members, whereby lateral displacement of said leaves is prevented when under such compression. It will be understood that these projections do not necessarily perforate and extend through the secured leaves, but serve to provide points of compression intensification.

Leaves may be added to the binder until the thickness thereof equals the vertical height of the shoulder 2a, at which time I prefer to remove the clamp-member 1 and slip one of the alignment strips 6 over the posts 3, said strips being provided with a bore 3b at each end thereof in properly spaced relation. The bores 3b are preferably formed in a sleeve or hub 3c so that the strips 6 are made readily slideable up and down the screw-posts 3, without catching in the threads thereof. The alignment strips 6 are preferably also provided with downwardly and upwardly projecting points 6d, each of said points being preferably formed by punching the metal strip so as to make a projection 6d on one side and a depression 6d' on the other side, and the member 1 is also preferably provided with a recess 1b' disposed opposite each of the upwardly projecting points on a member or element therebelow, so that, when the strips are in place in the binder, after the manner shown in Figs. 5 and 6, an upwardly projecting point 6d on a strip 6 will fit into a recess 1b' in the upper clamp-member 1 (Fig. 5), and a downwardly projecting point 1b 150

on the upper clamp-member 1 will fit into a recess or depression 6d' in the strip 6 (Fig. 6).

The above-mentioned alignment strips may be placed in position on the screw-posts 3 after the manner shown in dot-and-dash lines in Fig. 1, or as shown in full lines in Figs. 5 and 6. When the alignment strips are placed in such position (it being understood that these alignment strips are added one at a time, as the thickness of the accumulated paper leaves require the same) the lugs 6c will fit in the slots 2b, the leaves A' (Fig. 5) abutting in part against the shoulder 2a and in part against the lugs 6c, so that the rearward ends of said leaves are properly aligned in the binder. Fig. 5 shows the leaves inserted as above described, and with the alignment strip in loose engagement with the pile of leaves. With the binder in this condition, it may be picked up, turned so that the rearward edge is held downwardly, and tapped or jarred against any suitable surface, such as a table top, whereby the leaves are settled into position. The screws 4 may then be turned downwardly so as to bring the binder under compression, as shown in Fig. 6. Upon occasion that it is desired to remove or insert leaves, the binder is loosened, turned, and the rearward edge laid along a table top or the like, as above described, the desired leaves removed or inserted, and the binder tightened up. It is apparent that when the binder is loosened, the leaf engaging projections no longer subject the leaves to compression, and hence do not interfere in any way with the insertion or removal of leaves.

The form of device shown in Figs. 5 and 6 is similar in all major respects to the form of device first-described, but is shown as provided with a bottom backing-board 7, to which the lower clamp-member 2 may be secured in any suitable manner, as by means of a plurality of screws 8. This backing-board may extend laterally and longitudinally of the clamp-means to any desired extent, dependent upon the requirements of a particular need.

In Figs. 7, 8 and 9 I have shown an alternative form of the device of the present invention, which differs from the forms of device above described in providing a substantially closed rear wall or back for the binder, whereby the appearance of said binder is materially improved, and protection is provided to the rearward ends of the leaves within said binder. This last form of device is also shown as provided with a hinged upper cover, secured to the upper clamp-member, but it will be understood that this hinged cover is not peculiar to this form of invention, it being equally adaptable to either of the above-described forms of invention, or may, if desired, be eliminated from the present described form.

The present described form of binder may comprise a backing-board 11 to which is secured in any suitable manner a lower clamp-member 12 provided with a rearward shoulder 12a and two screw-posts 13 provided and disposed on said member after the manner of the posts 3 above-described, an upper clamp-member 14, screw nuts 15, and one or more removable alignment strips 16. The lower clamp-member 12 is provided with a plurality of slots 12b located in the shoulder 12a said slots extending downwardly from the upper edge of said shoulder after the manner of the slots 2b shown in Fig. 1, and are preferably three in number, appropriately spaced along the length of said member. The upper clamp-member 14 is provided with a rearward depending

shoulder 14a having a plurality of forwardly projecting lugs 14b equal in number and equivalent in spacing to the slots 12b and of such size as to enter said slots when the said upper clamp-member is brought downwardly into clamping position with respect to the lower clamp-member, the shoulder 14a overlapping the shoulder 12a. The lugs 14b preferably project forwardly a distance approximately equal to the thickness of the shoulder 12a, whereby the forward edge of said lugs are in substantially vertical alignment with the forward face of the shoulder 12a, against which the ends of the leaves A'' may abut and be aligned.

The alignment strips (but one of these strips being shown in Figs. 7 and 8) are preferably formed as shown in detail at 16 in Fig. 9 and may comprise a strip of metal provided with an upwardly extending shoulder 16a and a downwardly extending shoulder 16b, said upwardly extending shoulder being provided with a plurality of forwardly extending lugs 16d after the manner of the shoulder 14a. The strip 16 is also provided with a screw-post receiving bore at each end thereof, as shown at 16e, said bores being preferably formed in a sleeve or hub 16f after the manner of the bores 3b provided in the above-described strip 6.

The respective shoulders on the clamp-members and the alignment strips are so disposed that, as the clamp-member 14 is brought downwardly against a plurality of leaves A'', the forward faces of the shoulders 14a and 16b are in substantial alignment with the rearward faces of the shoulders 16a and 12a, respectively, with the lugs 14b fitting into the slots 16c and the lugs 16d fitting into the slots 12b, forming a substantially solid back for the binder as shown.

The upper clamp-member 14 may be provided, if desired, with a forwardly extending portion 14c to which is hingedly secured, as at 17, a cover member 18. This construction provides for protecting the bound papers on the bottom, back and top sides, after the manner of the conventional form of binder. It will be understood that the clamp-members and the alignment strips in the present described form of the invention may be provided with projecting paper-holding points such as shown at 1b, 2c and 6d in the first-described form of the invention, if desired.

Fig. 10 illustrates a form of sectional screw-post 3A, formed of a plurality of sectional elements 3A', which may advantageously be used in place of the screw-posts 3 or 13, whereby any desired height of binder may be obtained, merely by addition of elements 3A' to the screw-posts whereby the clamping means is extended to the desired degree, additional alignment strips being used after the manner above described. According to the form of binder desired, the strips 6 and 16 may be made with shoulders of such length as to accommodate approximately 200 leaves of average thickness before an additional strip is required.

I have used a binder, made after the first-described form of the present invention, to accommodate in excess of 1,000 leaves of average thickness, and, when sectional screw-posts are used therein, the extent to which the binder may be enlarged to accommodate additional leaves is limited only by the weight and bulkiness assumed thereby. The most important feature of

the present invention, in the eye of a prospective user of the device, lies in the fact that a binder, containing for example 800 leaves, may be loosened and 600 of the leaves removed bodily, a single leaf inserted, and the removed leaves replaced bodily, and the binder tightened up, or that the clamping means may be loosened and the desired leaves removed or inserted as above described, without disturbing the adjacent leaves.

10 I comprehend that numerous modifications of the essential conception of the present invention may be made by those familiar with the art, and I in no sense limit my invention to the specific forms described. For example, the slots 2b and the lugs

15 6c may be omitted from the lower clamp-member and the alignment strips, respectively, in the first form of the device, or, in the last-described form of the device the upper clamp-member 14 may be made after the manner of the upper 20 clamp-member 1 and the shoulder 14b provided on a separate alignment strip, or the like.

I claim:

25 1. A loose-leaf binder comprising upper and lower clamp members, compression means disposed adjacent the lateral extremities of said clamp members for forcing said members toward one another, and an alignment member disposed between said upper and lower clamp members and extending parallel thereto, said alignment member being provided with vertically extending shoulder means along the rearward edge thereof in position for aligning engagement by the ends 30 of leaves clamped in said binder.

35 2. A loose-leaf binder comprising upper and lower clamp members, compression means disposed adjacent the lateral extremities of said clamp members for forcing said members toward one another, upwardly extending shoulder means on the rearward edges of said lower clamp member positioned rearwardly of the rearward edge of said upper clamp member, an alignment member 40 removably disposed between said upper and lower clamp members and extending parallel thereto, said alignment member being provided with upwardly extending shoulder means along the rearward edge thereof in alignment with the aforesaid shoulder means, said first-named shoulder means being provided with a plurality of vertically extending slots disposed at intervals along 45 the length thereof, and said alignment member being provided with a plurality of depending lugs positioned for engagement in said slots.

50 3. A loose-leaf binder for securing a plurality of unpunched leaves comprising, upper and lower clamp members, compression means disposed ad-

jacent the lateral extremities of said clamp members for forcing said members toward one another, vertically extending shoulder means on the rearward edge of each of said clamp members in overlapping relation to one another, one of said shoulder means being provided with a plurality of vertically extending slots disposed at intervals along the length thereof, the other of said shoulder means being provided with projecting lugs positioned in vertical alignment with said slots, said one shoulder means and the lugs of said other shoulder means comprising alignment means for engagement of the ends of leaves clamped in said binder.

55 4. The invention set forth in claim 3, and comprising in addition, an alignment member removably disposed between said clamp members and extending parallel thereto, said alignment member being provided with upwardly and downwardly extending shoulder means adapted to overlap the shoulder means on the upper and lower clamp members respectively and provided with projecting lugs and with slots adapted for engagement with the slots and lugs respectively of the shoulder means on said clamp members.

60 5. A loose-leaf binder for securing a plurality of unpunched leaves, comprising, upper and lower clamp members, compression means disposed adjacent the lateral extremities of said clamp members for forcing said clamp members toward one another, downwardly extending shoulder means on said upper clamp member and upwardly extending shoulder means on said lower clamp member, said first-named shoulder means being spaced rearwardly of said second-named shoulder means and in overlapping relation thereto, said last-named shoulder means being provided with a plurality of upwardly extending slots disposed at intervals along the length thereof and said first-named shoulder means being provided with a 115 plurality of forwardly projecting lugs positioned in vertical alignment with said slots.

65 6. The invention set forth in claim 5, and comprising in addition, an alignment member removably disposed between said upper and lower clamp members and extending parallel thereto, said alignment member being provided with upwardly and downwardly extending shoulder means adapted to overlap the shoulder means on the upper and lower clamp members respectively 120 and provided with projecting lugs and with slots adapted for engagement with the slots and lugs respectively of the shoulder means on said clamp members.
